(57) **CLAIM**

The ornamental design for a game call, as shown and described.

DESCRIPTION

FIG. 1 is a front perspective view of the game call;
FIG. 2 is a top plan view thereof;
FIG. 3 is a left elevation view thereof;
FIG. 4 is a front elevation view thereof; and,
FIG. 5 is a right elevation view thereof.
The broken line showing of a game call is included for the
purpose of illustrating environment and forms no part of the
claimed design.
